UNITED STATES PATENT OFFICE.

JAMES A. McMILLEN, OF McDONALD, PENNSYLVANIA.

VALVE-BUSHING.

SPECIFICATION forming part of Letters Patent No. 739,614, dated September 22, 1903.

Application filed March 25, 1903. Serial No. 149,516. (No model.)

To all whom it may concern:

Be it known that I, JAMES A. McMILLEN, a citizen of the United States of America, residing at McDonald, in the county of Washington and State of Pennsylvania, have invented certain new and useful Improvements in Valve-Bushings, of which the following is a specification, reference being had therein to the accompanying drawings.

10 This invention relates to certain new and useful improvements in valve-bushings, and is particularly adapted for use in connection with that class of valves employed in pumps and the like, though the invention is applicable as well in any connection where a valve of this character is employed.

The object of my invention is to provide a substantially non-destructive and non-corrodible valve-bushing whereby to materially 20 lengthen the life of a valve and insure a more perfect working of the pump. In valves of this character the weakest point of the same is at the opening which receives the stem, and due to the constant movement of the valve 25 this portion of the valve soon becomes worn, so as to render the valve ineffective and requires the replacing of the same. The valves as generally employed are constructed entirely of rubber, as this has been found by far 30 the most desirable material, especially in connection with pumps where the water is impregnated with chemicals which readily destroy the elements of most materials.

My invention resides in the provision of a 35 bushing so secured in the valve as to be permanently held in position and which is constructed of a material to effectually withstand the constant working of the valve and the pounding of the same upon its seat.

40 Briefly described my invention consists in providing the valve-body usually constructed of rubber and provided with a central opening the walls of which are provided with recesses or grooves, preferably dovetailed in shape. The opposite sides of the valve-body 45 around the central opening are cored out and this cored-out portion together with the grooves or recesses in the walls of the central opening are filled with molten Babbitt metal, 50 which when it hardens forms a bushing firmly

held in position in the valve-body and which receives all of the wear to which the valve is subjected.

In describing the invention in detail reference is had to the accompanying drawings, 55 forming a part of this specification, and wherein like numerals of reference indicate like parts throughout the several views, in which—

Figure 1 is a central vertical sectional view through a portion of the pump, showing my 60 improved valves in position therein. Fig. 2 is a detail perspective view of the valve-body as constructed to receive the metal bushing. Fig. 3 is a detail perspective view of the complete valve, and Fig. 4 is a cross-sectional 65 view of the same.

In the accompanying drawings, 1 indicates the valve-body, preferably composed of hard rubber, though it will be evident that other material may be employed. This valve-body 70 is provided with a central opening 2 to receive the stem 3 of the valve. The walls of this opening 2 are provided with recesses or grooves 4, preferably made dovetail in shape, as shown, and the opposite side faces of the 75 valve-body are cored out on a bevel, as seen at 5 in Figs. 2 and 4, which cored-out portion together with the grooves 4 are filled with molten metal, preferably Babbitt metal, as this material has been found to be the most 80 satisfactory. This molten metal forms a bushing 6, which is effectually held in position by reason of a portion thereof lying within the cored-out portion 5 on opposite sides of the valve and the projections which are 85 in the dovetailed grooves 4.

In practice the valve is constructed as seen in Fig. 2 of the drawings. The core is then placed in the central opening 2, and the molten metal is run into the cored-out portion 90 and into the grooves and instantly hardens, producing the desired bushing.

In practice I have demonstrated that a valve constructed in this manner will last several times longer than the valve in which the 95 body proper comes in direct working contact with the stem. In practice the valves are held to their seats by means of springs 7, interposed between the valves and nuts 8 on the stems of said valves. However, I do not 100

desire to confine myself to this construction, as my invention resides in the metallic bushing placed in the valve-body, as stated, and in the practice of the invention it will be obvious that various slight changes may be made in the details of construction without departing from the general spirit of my invention.

Having fully described my invention, what I claim as new, and desire to secure by Letters 10 Patent, is—

1. In combination with a valve-body provided with a central opening and having beveled side faces surrounding said central opening provided with recesses, of a Babbitt metal 15 bushing countersunk in said side faces of the valve and having projections engaging in the recesses in the valve-body, substantially as described.

2. In combination with the valve - body 20 formed with an opening and having its opposite sides adjacent said opening cored out on a bevel, a bushing extending through said

opening and having its ends fitting in said cored-out portions of the valve-body.

3. In combination with the valve-body, provided with an opening and recesses communicating therewith, the opposite faces of said body adjacent said opening and recesses being cut away, a bushing having its ends enlarged and received in the cut-away portions 25 of said valve-body, and projections arranged between the enlarged ends of said bushing arranged in the recesses of said valve-body.

4. In a device of the type set forth a bushing having enlarged ends, projections arranged between said ends, said projections 30 tapering inwardly.

In testimony whereof I affix my signature in the presence of two witnesses.

JAMES A. MCMILLEN.
